ATTORNEY

UNITED STATES PATENT OFFICE.

ROBERT WEST, OF PORT HURON, MICHIGAN.

PIN-GUARD.

1,267,300.

Specification of Letters Patent. Patented May 21, 1918.

Application filed August 22, 1916. Serial No. 116,327.

To all whom it may concern:

Be it known that I, ROBERT WEST, a citizen of the United States, residing at Port Huron, in the county of St. Clair and State 5 of Michigan, have invented certain new and useful Improvements in Pin-Guards, of which the following is a specification.

My invention relates to a guard particularly for use on hat pins to cover the piercing point and thereby protect bystanders 10 against injury by the piercing point.

While the invention is primarily designed to accomplish the said end, yet it also serves as a loss preventing device as it grasps the 15 pin shank and cannot be readily dislodged therefrom.

I particularly aim to provide an article of this nature having grips of friction material, like rubber, to receive the pin shank between them, and if desired, to provide a container for the grip in the form of sections 20 hinged and fastened together.

With the above, and additional objects, such as will hereinafter appear, in view, the 25 invention has been embodied in one preferred form as illustrated in the accompanying drawings and hereinafter described.

In said drawings:—

Figure 1 is a view in elevation illustrating my invention in connection with a hat pin;

Fig. 2 is a longitudinal sectional view through the improved guard;

Fig. 3 is a cross sectional view through 35 the entire guard on the line 3—3 of Fig. 2;

Fig. 4 is a view of the guard looking at the pin insert end; and

Fig. 5 is an end view of a modified form of guard.

Referring specifically to the drawings, 40 wherein like reference characters designate like or similar parts for the purposes of explanation of the use of my improved guard, a hat pin is shown in Fig. 1 of which 1 is the piercing shank and 2 the head. This pin is to be taken as conventionally representing the style used by ladies and it is to be understood that the head 2 may be of any suitable or desired design.

The guard preferably has a plurality of 50 grips 6, preferably made of rubber or other friction material. The blocks within the guard are separate from each other and

preferably held in place by a suitable container or casing formed of sections 7 and 8, which are hinged together at 9. Any suitable means may hold the sections closed and against pivotal movement and to this end may be in the form of a latch leaf 10 of 55 spring metal adapted to coöperate with a lug 12. The lug 12 is carried by the section 7, while the latch 10 is carried by the section 8. It will be noted that the ends of the sections 7 and 8 are curved or formed so as to substantially completely close the grip 60 member 6. One end, however, of the sections 7 and 8 are cut away to provide an insert aperture 13 which is in the line of the abutting faces of grips 6.

With the construction shown, it will be 70 realized that as the pin 1 is passed through the aperture 13, it will extend intermediate the abutting faces of the grip 6 and which frictionally grips or grasps the shank. As a result the guard is maintained in place 75 protecting a bystander against injury from the point of the shank and also serving as a loss preventing device for the pin.

Since the grips are removable and similar in shape and size, they may be reversed in 80 the event the abutting faces of the grips opposite opening 13 become worn or dilated.

As stated, any suitable form of casing or housing may be provided for the grip and for instance as suggested in Fig. 5, the casing 85 is made in one piece as illustrated at 14, with the grip 6 being inserted and fastened in any suitable manner.

Other changes in the details of construction and arrangement of parts may be resorted to within the spirit and scope of the invention, as defined by the appended claims.

I claim:—

1. A guard of the class described having a 95 casing, a plurality of separate, inherently yieldable, removable grips within the casing, inwardly extending means on the casing to prevent bodily movement of the grips relatively to the casing, said casing having 100 an insert opening, and the said grips having faces in abutting relation opposite said openings to receive and grip a pin between them.

2. A guard of the class described having a 105 casing, a plurality of similar, separate, re-

versible, inherently yieldable grips within the casing, one end of the casing extending inwardly to prevent movement of the grips relatively to the casing in one direction, 5 means on the casing preventing movement of the grips in the opposite direction, said end having an insert opening therethrough, and the meeting faces of the grips being

closed and disposed opposite said opening to receive a pin between them. 10

In testimony whereof I affix my signature in presence of two witnesses.

ROBERT WEST.
